UNITED STATES PATENT OFFICE.

THOMAS H. THOMAS, OF EDGEWOOD, PENNSYLVANIA, ASSIGNOR TO THE WESTINGHOUSE AIR BRAKE COMPANY, OF WILMERDING, PENNSYLVANIA, A CORPORATION OF PENNSYLVANIA.

AUTOMATIC TRAIN-CONTROL DEVICE.

Application filed April 26, 1923. Serial No. 634,738.

This invention relates to an automatic train speed control equipment for controlling the speed of a train in accordance with the traffic conditions.

It has heretofore been proposed to provide a train speed control system in which means are provided whereby the engineer must acknowledge a signal indication in advance or the speed of the train will be automatically reduced to the low speed limit upon passing the signal indication.

If the road-side signal indication is not observed by the engineer in advance of the signal, then he must rely upon the cab signal. The cab signal indication only changes as the signal is passed and it is then too late for the engineer to acknowledge the signal indication in order to prevent the automatic operation of the speed control equipment to reduce the speed of the train to the low speed limit.

The principal object of my invention is to provide means for delaying the automatic operation of the speed control equipment for a predetermined time interval so that if the engineer acknowledges the signal indication within this time interval, the automatic operation of the speed control equipment will be prevented.

In the accompanying drawings; Fig. 1 is a diagrammatic view of an automatic train speed control equipment embodying my invention; Fig. 2 a sectional view of the main speed control valve mechanism of the equipment shown in Fig. 1, the parts being shown in high speed position; Fig. 3 a diagrammatic view, showing the manner in which the various elements of the speed control valve mechanism are charged with fluid under pressure; Fig. 4 a diagrammatic view, showing how certain parts of the speed control valve mechanism are affected in case the engineer fails to acknowledge a signal indication; and Fig. 5 a diagrammatic view, showing how certain parts of the speed control valve mechanism are affected in case the engineer acknowledges the signal indication within a predetermined time interval.

The automatic train speed control equipment shown in the drawings is in many respects similar to the train speed control equipment shown in my prior Patent No. 1,523,432, issued January 20, 1925, and com-

prising a main valve mechanism 1, a speed governor valve mechanism 2, an engineer's brake valve 3, an acknowledging valve 4, a main reservoir 5, an equalizing reservoir 6, a timing reservoir 7, a medium to low speed blow down reservoir 8, a stop reservoir 9, a high to medium speed blow down reservoir 10, and an acknowledging valve reservoir 11.

The main valve mechanism 1 includes an application valve device A, an equalizing discharge valve mechanism B, a change speed valve device C, a selector valve device D, a medium speed valve device E, an acknowledging piston device G, a high speed magnet valve device H, a medium speed magnet valve device K, a high to medium speed blow down valve device L, a medium to low speed blow down valve device M, and a feed valve device O.

The application valve device A comprises a piston 12 contained in piston chamber 13 and a slide valve 14 contained in valve chamber 15. The equalizing discharge valve mechanism B comprises a piston 16 having chamber 17 at one side connected by passage and pipe 18 to equalizing reservoir 6 and chamber 19 at the opposite side connected by passage 20 to the brake pipe 21. A valve 110 operated by piston 16 controls the venting of fluid under pressure from the brake pipe 21 to effect an application of the brakes.

The change speed valve device C comprises differential pistons 22 and 23, the smaller piston 22 being contained in piston chamber 24 and the larger piston in piston chamber 25. The valve chamber 26 intermediate the pistons 22 and 23 contains a slide valve 27 adapted to be operated by said pistons.

The selector valve device D comprises a piston 28 contained in piston chamber 29 and a slide valve 30, contained in valve chamber 31. The medium speed valve device E comprises a piston 32 contained in piston chamber 33 and a slide valve 34 contained in valve chamber 35.

The acknowledging valve device 4 comprises a casing containing a rotary valve 36 and a handle 37 for operating said valve. The high speed magnet valve device H comprises a magnet 38 and double beat valves 39 and 40 controlled by said magnet and the medium speed magnet valve device K com-

prises a magnet 41 and double beat valves 42 and 43 controlled by said magnet.

The high to medium speed blow down valve device L comprises a valve piston 44 and valves 45 and 46 operable by said valve piston and the medium to low speed blow down valve device M comprises a valve piston 47 and valves 48 and 49 operable by said valve piston.

10 The acknowledging piston device G comprises a piston 50 contained in piston chamber 51, a piston valve 52 and a poppet valve 53 operable by said piston. The speed governor valve mechanism comprises a speed 15 governor P operatively connected so as to rotate at a speed proportional to the speed of the train, a crosshead 54 operable by said governor, and a plurality of valves 55 adapted to be operated according to the extent of 20 movement of the crosshead 54.

There is also provided a stop reservoir valve device comprising a piston 56 and a valve 57 operable by said piston and a stop valve device comprising a piston 58 and a 25 valve 59 operable by said piston.

The construction so far described is similar to that of my prior Patent No. 1,523,462, hereinbefore referred to, and in addition, according to my present invention, there is 30 provided means for allowing a time interval within which a signal indication may be acknowledged by the engineer. The construction is preferably designed so that the time interval is allowed only when the change in

35 the signal indication is from high speed to medium speed and comprises a valve mechanism which functions to delay, for a predetermined period of time, the movement of the change speed valve device from its high speed position to either its lower or its medium speed position, so that if during this time interval, the engineer acknowledges the signal indication as given in the cab, the change speed valve device will be shifted to 40 its medium speed position, otherwise, if the engineer fails to acknowledge the signal indication during this time interval, the change speed valve device will be shifted to its low speed position.

45 For accomplishing the above purpose, a relay piston 60 is provided, which is contained in a piston chamber 61 connected by pipe 62 to timing reservoir 7. The piston 60 is adapted to operate a relay discharge valve 55 and also a charging valve 64. There is also provided a delay piston 65 adapted to operate valves 66 and 67.

When the signal indication is for high speed, the electric control is such that the high speed magnet 38 will be energized and the medium speed magnet deenergized and the parts will be charged with fluid under pressure as follows: Fluid under pressure flows from the main reservoir 5 through pipe 69 and passage 70 to passage 71 and

thence through connecting passages to valve chamber 15 of valve device A, valve chamber 26 of valve device C, valve chamber 31 of valve device D, valve chamber 35 of valve device E and to feed valve device O 70 which then supplies fluid at a reduced pressure to charge the feed valve reservoir 72. The timing reservoir 7 is charged in the high speed position from the main reservoir through passage 73, past the open valve 40 of the high speed magnet valve device H to passage 74, and thence past the open valve 67 to a passage 76 leading to the timing reservoir pipe 62.

When the timing reservoir 7 is charged 80 with fluid under pressure, the relay piston 60 operates to close the relay discharge valve 63 and open the charging valve 64, permitting fluid from the main reservoir to charge the piston chamber 25 of the change speed 85 valve device C through passage 77, which communicates with passage 71, past the charging valve 64 to passage 78, passage 79 and through the acknowledging piston device G to passage 80, cavity 81 in slide 90 valve 80 to passage 82 and thence to the piston chamber 25. The other piston chamber 24 of the change speed valve device being supplied with fluid under pressure from valve chamber 31 of the selector valve device D through passage 83, the change speed valve device will be maintained in its intermediate high speed position, as shown in Fig. 2.

When the signal indication changes from 100 high speed to medium speed, the high speed magnet 38 becomes deenergized and the medium speed magnet 41 energized. The deenergization of the high speed magnet 38 causes the valve 40 to seat and the valve 39 105 to open, so that fluid under pressure will be vented from the timing reservoir 7 through passage 76, and thence through a restricted port 84 to passage 74, the check valve 75 preventing flow in that direction through the 110 larger port opening. From passage 74 fluid is vented to exhaust port 85 past the valve 39.

115 In connection with the above operation it should be noted that there is also a direct communication from the passage 76 to the passage 74 which is controlled by the valve 67, the restricted port 84 being in a by-pass connection around said valve, but this direct communication is now closed by the valve 67 because the medium speed magnet K being 120 energized when a medium speed signal indication is received, fluid from the main reservoir 5 is supplied to the delay piston 65 through passage 93, past the open valve 43 to passage 94 which leads to the piston chamber at the face of piston 65. The piston 65 is therefore operated to seat the valve 67. It will thus be seen that it requires a certain time interval for the pressure in the timing reservoir 7 to reduce by 130

flow through the restricted port 84 and until the pressure in the timing reservoir 7 has been reduced to a predetermined degree, the relay piston 60 will remain in its upper 5 position.

If the engineer fails to acknowledge the signal indication, the acknowledging piston 50 will remain in its outer position, establishing communication from piston chamber 10 25 to passage 78 by way of passage 82, cavity 81 in slide valve 30, passage 80, and past the open valve 52 to passage 79, so that when the pressure in the timing reservoir 7 has been reduced to predetermined degree by flow 15 through the restricted port 84 and out at the exhaust port 85, the piston 60 will move to close the valve 64 and open valve 63, permitting the venting of fluid from piston chamber 25 through passage 78 and past the 20 open valve 63 to the atmosphere. The change speed valve device will then be shifted to its low speed position, so that the speed control mechanism will then operate to reduce the speed of the train to the low 25 speed limit. The operation as above described where the signal indication changes from high speed to medium speed and the signal indication is not acknowledged is shown diagrammatically in Fig. 4.

If the signal indication changes from high speed to medium speed and the engineer acknowledges the signal indication by moving the acknowledging valve to its acknowledging 35 position during the time interval in which the pressure in the timing reservoir 7 is being reduced fluid under pressure will be supplied to the acknowledging piston 50 from the acknowledging reservoir 11, through pipe 96, passage 97, cavity 98 in slide valve 14, and the piston 50 will then be shifted so as to cause the valve 52 to cut off communication from passage 79 to passage 80 and consequently when the piston 60 moves downwardly upon depletion of the 40 fluid pressure in the timing reservoir 7, although the discharge valve 63 will be opened, fluid under pressure will not be vented from the piston chamber 25 of the change speed valve device C.

The movement of the acknowledging piston 50, however, operates to open the valve 53, so that fluid under pressure is vented from piston chamber 29 of the selector valve 45 device D through passage 86, past the open valve 53 to passage 79 and thence to the atmosphere through passage 78, past the open valve 63. The selector piston 28 will then be shifted to its outer position, thereby moving the slide valve 30 so as to cut off communication from the piston chamber 25 of the change speed valve device C to the 50 passage 80.

The movement of the selector piston 28 and slide valve 30 to the outer position results in establishing communication from 60

the spring side of the high to medium blow down valve piston 45 and also the high to medium reservoir 10 to the blow down timing exhaust as controlled by the speed governor valve mechanism 2 by way of passages 70 87 and 88, cavity 89 in slide valve 30 and passage 90, which is connected by pipe 91 to the speed governor valve mechanism.

When the pressure in the reservoir 10 and at the spring side of the valve piston 45 has 75 been reduced to a predetermined degree, the valve piston is operated to open valve 46 so that fluid under pressure is vented from piston chamber 24 of the change speed valve device C to the atmosphere by way of passage 83, past the open valve 46 to exhaust port 92. The change speed valve device C will then be shifted to its medium speed position, as shown in the diagram Fig. 5. In 80 the medium speed position of the change speed valve device C, the piston chamber 13 of the application valve device A is connected to one of the valves 55 controlled by the speed governor P, so that if the speed of the train exceeds the medium speed limit, 85 fluid will be vented from piston chamber 13 of the application valve device and said valve device will then be operated to effect an application of the brakes.

The timing interval provided as hereinbefore described, within which the engineer may acknowledge a change in the signal indication without being subjected to the penalty of having the speed limit of the train reduced to the low speed limit is not 95 desirable in case the signal indication changes from high speed to low speed instead of from high speed to medium speed, due for example, to a train on a side track entering the main track, since in such event, 100 the brake application and the checking of the speed of the train should be obtained as promptly as possible.

Means are therefore provided for cutting the acknowledgment delay feature out of 110 action when the signal indication changes from high directly to low speed.

For accomplishing the above purpose, when the medium speed magnet 41 is energized due to receiving a medium speed signal indication, the valve 43 is opened so that fluid under pressure is supplied to piston 65 from the main reservoir 5 by way of passage 93, past the open valve 43, and passage 94. The piston 65 is then operated 115 to close the valve 67 which closes a large port connection from passage 76 to passage 74 and the venting of fluid from the timing reservoir 7 is limited to a rate as determined by the restricted port 84, so that the desired 120 time interval is provided.

When the signal indication changes from 125 high speed directly to low speed, the medium speed magnet 41 remains deenergized, as it was when the signal indication was at high 130

speed, so that the valve 43 is held closed while the valve 42 is held open. The piston 65 is consequently open to the atmosphere by way of passage 94, past the open valve 42 to exhaust port 95 and valve 67 will remain in its open position.

Fluid under pressure will then be vented from the timing reservoir 7 at a rapid rate by way of passage 76, past the open valve 67 to passage 74 and thence past the open valve 39 controlled by the high speed magnet 38 to the exhaust port 85. The pressure in the timing reservoir 7 is thus quickly reduced and consequently the piston 60 is quickly operated to open the valve 63, so that substantially no time interval elapses before the change speed valve device C is operated by the venting of fluid pressure from piston chamber 25, so that said change speed valve device promptly moves to its low speed position.

The object of the charging valve 64 is to provide means for charging the piston chamber 25 of the change speed valve device C when the signal indication changes from low speed to high speed, so that the change speed valve device will be shifted to its high speed position. When the signal indication changes to high speed, the high speed magnet 38 becomes energized, so that fluid under pressure is supplied by the opening of valve 40 to the timing reservoir 7 and piston chamber 61 of the relay piston 60. Upon restoration of fluid pressure, the piston 60 is operated to close the valve 63 and open the charging valve 64, so that fluid under pressure is supplied to the piston chamber 25 of the change speed valve device C from passage 79, past the open valve 64 to passage 78 and thence through passage 79, passage 80, cavity 81 in slide valve 30, and passage 82 to piston chamber 25. The increase in pressure in piston chamber 25 will then operate to return the change speed valve device C to its high speed position.

On account of the relatively small volume of the piston chamber 13 of the application valve device A, it has been found that there is a possibility that the application piston may move to application position when not intended, through the creation of a slight differential pressure, due to possible leakage in the pipes and passages connected to said chamber and in order to avoid this possibility, another feature of my invention consists in providing an application reservoir 100, the volume of which is connected to the application piston chamber 13 by way of pipe 101, passage 102, and passages 103 and 104.

The reservoir 100 may be charged from the main reservoir 5 through a pipe 105 containing a choke fitting 106 having a restricted port through which fluid under pressure is supplied to said reservoir and the pipe 101

may be provided with a check valve 107 for preventing back flow from the piston chamber 13 to the reservoir 100.

Having now described my invention, what I claim as new and desire to secure by Letters Patent, is:—

1. In a train speed control apparatus, the combination with valve means responsive to a change in the signal indication for determining the speed limit of the train, of means for delaying the operation of said valve means after the signal indication is received and independently of the speed of the train, for a definite and substantial period of time and sufficient to permit the engineer to act. 75

2. In a train speed control apparatus, the combination with valve means responsive to a change in the signal indication for determining the speed limit of the train, of means for delaying the operation of said valve means after the signal indication is received and independently of the speed of the train, for a substantial predetermined time interval, said time interval being sufficient to permit of a manual operation by the engineer. 90

3. In a train speed control apparatus, the combination with mechanism responsive to a change in the signal indication for fixing the speed limit of the train, of means operative by the engineer for determining the speed limit to be fixed by operation of said mechanism and means for delaying the operation of said mechanism for a fixed time interval after receiving a signal indication to provide a time interval within which the engineer may act after receiving the signal indication. 100

4. In a train speed control apparatus, the combination with a valve device movable upon a change in the signal indication to a position for effecting a change in the speed limit of the train, of means for delaying the movement of said valve device for an extended predetermined time interval which is independent of the speed of the train. 110

5. In a train speed control apparatus, the combination with a mechanism having a tendency to move to a position for effecting a change in the speed limit of the train due to a change in the signal indication, of means for delaying the operation of said valve device for a predetermined time interval and means operable by the engineer during said time interval for effecting the movement of said mechanism to another position in which said mechanism is effective to fix a different train speed limit. 115

6. In a train speed control apparatus, the combination with a valve device operative to fix the speed limit of the train and having high, medium, and low speed limit positions and means operative upon a change in the signal indication from high speed to medium speed for effecting the movement of said valve device to its low speed position 130

and means for delaying the operation of said valve device for a predetermined time interval.

7. In a train speed control apparatus, the combination with a valve device having a piston subject to fluid under pressure and operative to determine the speed limit of the train, of a timing reservoir normally charged with fluid under pressure, a valve device operative upon a reduction in pressure in said reservoir for venting fluid from said piston, and means responsive to a change in the signal indication for venting fluid from said reservoir.

15 8. In a train speed control apparatus, the combination with a valve device having a piston subject to fluid under pressure and operative to determine the speed limit of the train, of a timing reservoir normally charged with fluid under pressure, a valve device operative upon a reduction in pressure in said reservoir for venting fluid from said piston, means responsive to a change in the signal indication for venting fluid 20 from said reservoir, and means under the control of the engineer for controlling communication through which fluid is vented 25 from said piston.

9. In a train speed control apparatus, the combination with a valve device movable to different positions for fixing the speed limit of the train and having pistons normally subject to fluid under pressure, of a timing reservoir normally charged with fluid under 30 pressure, a valve device operated upon a reduction in pressure in said reservoir for venting fluid under pressure from one piston, a valve mechanism movable to a position for venting fluid under pressure from 35 the other piston, means responsive to a change in the signal indication for venting fluid from said reservoir, and means operable by the engineer for effecting the operation of said valve mechanism.

45 10. In a train speed control apparatus, the combination with valve means responsive to a change in the signal indication from high speed to medium speed or from high speed to low speed for fixing the speed limit of the train, of means for delaying the operation of said valve means for a time interval when the signal indication changes from high speed to medium speed and means for permitting the operation of said valve means 50 without delay when the signal indication changes from high speed to low speed.

11. In a train speed control apparatus, the combination with valve means responsive to a change in the signal indication for fixing the speed limit of the train, of a timing reservoir normally charged with fluid under pressure, a valve device operated upon a predetermined reduction in pressure in said reservoir for effecting the operation of said 60 valve means and means controlled by a

change in the signal indication for venting fluid from said reservoir and for determining the rate at which fluid is vented from said reservoir.

12. In a train speed control apparatus, the combination with valve means responsive to a change in the signal indication for fixing the speed limit of the train, of a timing reservoir normally charged with fluid under pressure, a valve device operated upon 75 a predetermined reduction in pressure in said reservoir for effecting the operation of said valve means and means controlled by a change in the signal indication from high speed to medium speed for venting fluid 80 from said reservoir at a restricted rate and upon a change in the signal indication from high speed to low speed for venting fluid from said reservoir at a more rapid rate.

13. In a train speed control apparatus, the combination with a change speed valve device having a piston normally subject to fluid under pressure, of a timing reservoir, a valve mechanism having a piston subject to the pressure in the timing reservoir and 90 operative upon a predetermined reduction in pressure in said reservoir for venting fluid under pressure from the piston of the change speed valve device and magnet controlled valve means operative upon a change 95 in the signal indication for venting fluid from said timing reservoir.

14. In a train speed control apparatus, the combination with an application valve device having an operating piston contained in 100 a piston chamber normally charged with fluid under pressure, of a volume reservoir connected to said piston chamber and means for effecting a rapid recharge of only the piston chamber, following a reduction in 105 pressure in said chamber and said reservoir.

15. In a train speed control apparatus, the combination with an application valve device having an operating piston contained in 110 a piston chamber normally charged with fluid under pressure, of a volume reservoir connected to said piston chamber, means for charging said reservoir through a restricted port, and a check valve for preventing back flow from said piston chamber 115 to said reservoir to permit a rapid recharge of the piston chamber following a reduction in pressure therein.

16. In a train speed control apparatus, the combination with a change speed valve device having an operating piston contained 120 in a piston chamber, of a timing reservoir normally charged with fluid under pressure, valve means for controlling the admission and release of fluid under pressure to and from said piston chamber, and a piston subject to the pressure in said timing reservoir for controlling the operation 125 of said valve means.

17. In a train speed control apparatus, the 130

combination with a change speed valve device having an operating piston contained in a piston chamber, of a timing reservoir normally charged with fluid under pressure, 5 a valve for venting fluid under pressure from said piston chamber, a valve for supplying fluid under pressure to said chamber, and a piston subject to the pressure in said reservoir for controlling the operation of 10 said valves.

18. In a train speed control apparatus, the combination with means responsive to a change in the signal indication for determining the speed limit of the train, of means 15 for delaying the operation of said signal indication responsive means for a time interval after the signal indication is received and independently of the speed of the train, said time interval being of substantial duration such as to permit action by the 20 engineer.

19. In a train control apparatus, the combination with an application valve device having an operating piston contained in a piston chamber and means operated by said 25 piston upon a reduction in fluid pressure in said chamber for effecting an application

of the brakes, of a volume reservoir connected to a source of fluid under pressure through an always open restricted port and 30 connected at all times to said piston chamber through a relatively unrestricted communication whereby the flow of fluid from the reservoir to the piston chamber is at a greater rate than the flow of fluid from the 35 source of pressure to the reservoir.

20. In a train control apparatus, the combination with a main reservoir, of an application valve device having an operating piston contained in a piston chamber and 40 means operated by said piston upon a reduction in fluid pressure in said chamber for effecting an application of the brakes and a volume reservoir charged from the main reservoir through a restricted port and 45 connected to said piston chamber through an always open communication such that fluid under pressure will flow from the reservoir to the piston chamber at a greater rate than fluid under pressure can flow from the 50 main reservoir to said volume reservoir.

In testimony whereof I have hereunto set my hand.

THOMAS H. THOMAS.
